(57) CLAIM

The ornamental design for eyeglass temples, as shown and described.

DESCRIPTION

FIG. 1 is a left side elevation view of the eyeglass temples showing the new design, the right side elevation view being a mirror image thereof;

FIG. 2 is a top plan view thereof;

FIG. 3 is a bottom plan view thereof;

FIG. 4 is a rear elevation view thereof; and,

FIG. 5 is a front elevation view thereof.

In the foregoing figures, the portion illustrated in broken line depicts the frame of the eyeglasses to which the eyeglass temples may be attached, and indicia on a forward portion of the temple in FIG. 1, both of which form no part of the claimed design.
